COVER ATTACHMENT FOR
TELEPHONE HANDSETSJames Russell Price, Esmond, R.I., assignor to
Gorham Corporation, Providence, R.I.

Filed Aug. 10, 1966, Ser. No. 3,417

Term of patent 14 years

(Cl. D26—14)

FIG. 1 is a side elevation of a cover attachment for telephone handsets, showing my new design,

FIG. 2 is an end view thereof, the opposite end being substantially the same except for omission of the aperture,

FIG. 3 is a top plan view thereof, the right-hand portion of the decorative motif fragmentarily shown, is a mirror image of the left-hand portion shown; and,

FIG. 4 is a sectional view taken on the line 4—4 of FIGURE 3.

The decorative motif is omitted from FIGS. 1 and 2 for ease of illustration.

The broken lines representing the telephone handset is shown for illustrative purposes only.

I claim:

The ornamental design for a cover attachment for telephone handsets, as shown and described.
